(57) **CLAIM**

The ornamental design for a rifle adapter for pistol ammunition, as shown and described.

DESCRIPTION

FIG. 1 is an isometric view of the rifle adapter for pistol ammunition, which embodies my design;
FIG. 2 is an isometric view of the rifle adapter for pistol ammunition;

FIG. 3 is a side view of the rifle adapter for pistol ammunition;

FIG. 4 is a side view of the rifle adapter for pistol ammunition;

FIG. 5 is a top plane view of the rifle adapter for pistol ammunition;

FIG. 6 is a bottom plane view of the rifle adapter for pistol ammunition;

FIG. 7 is a front view of the rifle adapter for pistol ammunition;

FIG. 8 is back view of the rifle adapter for pistol ammunition;

FIG. 9 is a side view of the rifle adapter for pistol ammunition; and,

FIG. 10 is an isometric view of the lever portion of the rifle adapter for pistol ammunition to show detail not otherwise discernible from the drawings.

The components depicted by broken lines in FIG. 9 have been shown for the purposes of illustrating environmental features that form no part of the claimed design.
